UNITED STATES PATENT OFFICE.

STANLEY C. SLATER, OF BOLTON, ENGLAND.

SURGICAL SPLINT.

No. 874,446.

Specification of Letters Patent.

Patented Dec. 24, 1907.

Application filed January 21, 1907. Serial No. 353,308.

To all whom it may concern:

Be it known that I, STANLEY CAMERON SLATER, British subject, and resident of Bolton, in the county of Lancaster, England, 5 have invented certain new and useful Improvements in Surgical Splints, of which the following is a specification.

This invention relates to certain improvements in surgical splints to render them adjustable to limbs of different lengths.

Each splint comprises in its construction a pair of tubular rods with external screws and nuts fitting on the extremities, a pair of rods adjustably fitting into the tubes at one end, 15 provided with an annular metallic pad or girth attached to both, and a pair of rods adjustably fitting into the tubes at the other end provided with a "rest" or "patten".

The invention will be fully described with 20 reference to the accompanying drawings forming part of the specification.

Figure 1. is a perspective view showing the splint arranged as a hip splint. Fig. 2. is a sectional elevation of one end of the tubular rod showing the means for securing the parts together. Fig. 3. is an elevation of lower extension end forming a knee splint. Fig. 4. is a sectional plan of same. Fig. 5. is an elevation of lower extension end comprising two 30 rods to engage an ordinary boot.

The splint or appliance is constructed with two tubular rods A the ends of which are slitted at *a* and externally provided with a screw thread to which are attached at one 35 end a hip pad or girth B by rods *b* attached thereto, and at the other end a rest C or patten C' by rods *c*.

The ends of the tubular rods are tapered and fitted with tapering nuts D by which the 40 ends can be contracted to grip or engage the rods *b* or *c* inserted therein.

The rods *b* are firmly affixed to the hip pad B and pass down into the tubular rods A where they can be adjusted to any desired 45 position and firmly clamped by the nuts D. Likewise the rods *c* affixed to the rest C or patten C' pass into the tubular rods A at the other end and when adjusted are clamped by the nuts D.

The base of the rest C is rigidly affixed to 50 the rods *c* and is preferably circular and the "patten" is hinged or pivoted on pins *c'* so that it may be adjusted to any angle.

Separate rods *c'* may be employed to affix 55 to a boot or shoe E.

To the hip pad or girth B a bar F may be attached to connect it with a body girth or belt G provided with a strap and buckle or other fastening device to secure the splint to the body of the wearer. To insure the body 60 girth or belt G being comfortable to the wearer it is padded and covered with chamois leather or other suitable covering.

A piece H of canvas or other flexible material is attached to the two metallic tubes A to 65 form a support and attachment by which to adjust the splint to the leg of the patient.

What I claim as my invention and desire to protect by Letters Patent is:—

1. In a surgical splint the combination 70 with two tubular rods each slit at the ends and provided with screws and nuts to screw thereon of a hip pad, rods projecting therefrom to enter the hollow rods A and capable of adjustment therein, and a foot rest with 75 rods to enter the other ends of the hollow rods and be secured therein substantially as described and shown.

2. In a surgical splint the combination 80 with two tubular rods each slit at the ends and provided with screws, and nuts to screw thereon of a hip pad, rods projecting therefrom to enter the hollow rods A and capable of adjustment therein, and a foot rest with 85 rods to enter the other ends of the hollow rods and be secured therein, a body girth and a bar to attach it to the hip pad, substantially as described.

In witness whereof, I have hereunto signed my name in the presence of two subscribing 90 witnesses.

S. C. SLATER.
